UNITED STATES PATENT OFFICE.

WILLIAM P. CANNING, OF LOWELL, MASSACHUSETTS, ASSIGNOR TO THE
LOWELL MACHINE SHOP, OF SAME PLACE.

TRAVELING-FLAT CARDING-ENGINE.

SPECIFICATION forming part of Letters Patent No. 451,367, dated April 28, 1891.

Application filed July 31, 1890. Serial No. 360,586. (No model.)

To all whom it may concern:

Be it known that I, WILLIAM P. CANNING, a citizen of the United States, residing at Lowell, in the county of Middlesex and State 5 of Massachusetts, have invented a new and useful Improvement in Traveling-Flat Carding-Engines, of which the following is a specification.

My invention relates to traveling-flat carding-engines, and is applicable to carding-engines in which there is a lateral opening between any part or all of the flexible bend and the main bend, through which air, flyings, or any substance can pass from side to side of the bends. It is especially applicable to any 15 carding-engine in which the inner faces of the flexible and the main bends are in the same plane or substantially in the same plane.

The object of my improvement is to prevent 20 the passage of air, flyings, or substances of any kind through such an opening and to steady the flexible bend in position. To this end I close any such opening between the flexible and the main bends by a covering- 25 plate mounted upon the main bend on the side thereof opposite to the brackets which support the flexible bend.

Figure 1 of the annexed drawings is a partial side view of a carding-engine to which my 30 improvement is applied. Figs. 2, 3, and 4 are partial sections of different modifications of the same, taken at the line SS of Fig. 1. Fig. 2 represents the application of the covering-plate in a case when the flexible bend is over 35 the main bend with the inner faces of the two bends in the same plane or substantially in the same plane. In Figs. 3 and 4 the flexible bend is represented with a rabbet or recess in its interior face, while in Fig. 2 no such rabbet 40 appears. In Fig. 4 the covering-plate is represented as being an integral part of the main bend and as being proportionately thicker than it is represented to be in Figs. 2 and 3. Fig. 5 is a section of the flexible and main 45 bends and covering-plate through one of the supporting-brackets. Fig. 6 is a view similar to Fig. 1, but showing the connection between the flexible bend and the supporting slides or brackets therefor, indicating the chain of 50 traveling flats by dotted lines, and showing

various rollers and supporting-brackets employed in connection with said chain.

In the figures, F represents the frame of the carding-engine; B, the main bend; b, the flexible bend; C, the main cylinder; C', the 55 shaft of the main cylinder; a', the covering-plate; a³, the space between the flexible and the main bends, through which substances could pass from side to side of the bends were it not for the covering-plate a'.

s s, Figs. 1, 2, 3, 5, and 6, are screws or other fastenings, by the aid of which the covering-plate a' is attached to the main bend.

P P' P'' P''' are protectors for the edges of the wire clothing upon the main cylinder or 65 upon the flats.

f designates the flats, and p p' p² the brackets which support the studs that carry the flexible bend.

In Figs. 1 and 6 the covering-plate a' a' is 70 represented by dotted circular arcs; but its outline might have a different shape from that represented in said figures. The plate will serve its purpose as a covering-plate if it shall be everywhere sufficiently wide to substantially prevent the passage of substances of any kind through the space a³ a³ from 75 side to side of the bends in any position of adjustment of the flexible bend.

In Figs. 2 and 3, a' is represented as a some- 80 what thin covering-plate, preferably of steel, which is of sufficient width to overlap a portion of the main bend, a portion of the flexible bend, and the space between them. It prevents the passage of substances of any 85 kind through the space a³ a³.

In Fig. 3 both the flexible bend b and the main bend B are rabbeted on their inner faces. Generally I prefer to make the depth of the rabbet in the flexible bend and the 90 depth of the rabbet in the main bend substantially equal to the thickness of the plate a' a', so that the inner faces of these three parts shall be in the same plane.

In Fig. 2 no rabbet is represented either in 95 the flexible or in the main bend; but the inner faces of both of those pieces are in the same plane with the outer face of the covering-plate a'.

In Fig. 4 the plate a' is represented as be- 100

ing an integral part of the main bend, and as being proportionately thicker than it is represented to be in Figs. 2 and 3. The plate a' , when formed as a separate plate, may be attached to the main bend B by bolts, screws, rivets, or other fastenings. In Figs. 1, 2, and 3 countersink-headed screws are represented as put through the plate a' from the inside and screwed into the main bend. I prefer to attach the plate to the main bend by the aid of such screws. Whenever the plate a' is used, the flexible bend b is bounded, confined, and steadied in position between the plate a' on the inside and the brackets or their accessories, which support the studs that carry the flexible bend, on the outside; and this is a distinct improvement. A part of one such bracket p is represented in Fig. 5 with the flexible bend b between it and the plate a' . In Fig. 6 I have shown supporting and adjusting slides $p p' p^2$ of a kind in common use. These slides are slotted, as at p^3 , to permit of adjustment, and are secured in place by bolts and nuts p^4 . One of these slides—namely, that lettered p—is represented as carrying a pin or stud s^3 , which is secured to it in a fixed position by one end, while the other end of the stud enters a circumferential slot t in the flexible bend. Another of these slides p' is represented as carrying a stud s' , which is secured to it in a fixed position by one end, while the other end of the stud enters a round hole in the flexible bend. The third slide or bracket p^2 is represented as having a slot t^2 , into which the pin s^2 enters, the pin being secured to the flexible bend in a fixed position. In connecting either end of the flexible bend with its adjacent adjusting and supporting slide or bracket the slot may be in the bracket or the pin may be secured to the latter, as may be preferred. The screws $q q' q^2$, if turned one way or the other, cause the slides or brackets to move toward or away from the axis of the main cylinder. The slides or brackets lettered r and r' are those which in practice support the grinding-roller and the roller by which the chains carrying the flats are tightened.

In Figs. 2 and 4 are shown well-known forms of protectors for the edges of the working-surfaces of the card-clothing upon the main cylinder and upon the flats. One of these protectors P consists of an angle-plate placed upon the leather or other backing of the card-clothing of each of the flats and screwed or riveted in place, one portion thereof standing in a vertical plane parallel with the teeth

upon the said card-clothing. Another protector P' consists of a ring or plates secured by screws to the end of the cylinder C and projecting at the side of the teeth on the cylinder to or near the points thereof. The protector P'' consists of a short piece of iron or steel wire of rectangular section. The leather or other backing of the card-clothing of the flat is extended outward beyond the teeth of the said clothing between the wide face of the flat and the protector P'', and the ends of the protector P'' are bent around the edges of the flat and compressed into narrow grooves, which run lengthwise of the flat near to the edges of the wide flange to which the clothing is fastened. The protector P''' consists of a ring or plates screwed to the end of the cylinder and extending alongside of and parallel with the teeth on the cylinder and flats. Any other good forms of protector may be substituted. I do not claim the invention of the protectors herein described.

Although I have herein shown the flexible bend placed in substantially the same vertical plane with the main web of the main bend and the main bend notched or recessed at its outer edge, with the flexible bend located in the notch or recess, I do not herein lay claim to this feature *per se*, inasmuch as it is claimed in an application filed on even date herewith by Channing Whitaker, of Tyngsborough, Massachusetts, and myself as joint inventors, and bearing the serial number 360,588.

I claim—

1. The combination, with the flexible bend and the main bend, of the brackets carried by the main bend and supporting the flexible bend, and the covering-plate on the opposite side of the main bend from the brackets, substantially as described.

2. The combination, with the flexible bend, rabbeted as described, of the main bend and the covering-plate thereon projecting over the rabbeted portion of the flexible bend, substantially as described.

3. The combination, with the flexible bend and the main bend, both rabbeted, as described, of the covering-plate secured to the main bend and projecting over the rabbeted portion of the flexible bend, substantially as described.

WM. P. CANNING.
